UNITED STATES PATENT OFFICE.

GERARD BROOK RILEY AND HERBERT OCTAVIUS MOCK, OF LONDON, ENGLAND.

SUBMARINE MINE.

1,295,064.

Specification of Letters Patent. Patented Feb. 18, 1919.

Application filed January 17, 1918. Serial No. 212,370.

To all whom it may concern:

Be it known that we, GERARD BROOK RILEY, commander R. N., and HERBERT OCTAVIUS MOCK, lieutenant commander R. N. 5 V. R., subjects of the King of England, residing in London, England, have invented certain new and useful Improvements in Submarine Mines, of which the following is a specification.

- 10 This invention relates to sinkers or anchors for submarine mines of the kind in which the mooring cable or the like connecting the mine and sinker is carried on a winding drum, from which it is paid out as the sinker falls to the bottom, the winding drum being provided with a ratchet coöperating with a spring pawl which is adapted to be held away from the ratchet by a plummet weight during laying of the mine.
- 15 The object of this invention is to provide a locking device which coöperates with the winding drum to lock positively the same against rotation at a desired interval after the mine and sinker enter the water, thereby preventing any rotation of the drum, and any further paying out of the mooring cable, even if the springs of the pawl should break to allow the pawl to fall away from the ratchet.
- 20 A locking device according to this invention comprises a member connected to the pawl or pawls of the winding drum, and adapted to have limited sliding movement through an aperture in the shell of the sinker 35 or in part connected therewith, the member being provided with locking arms which while able to pass upward through the aforesaid aperture, will take up the locking position after passing completely through the same to prevent any return of the member, and so keep the pawls up to ratchet. The lower end of the member is connected to the plummet.
- 25 To prevent any premature return of the member to locking position, a catch may be provided operated by a hydrostatic valve, to engage the member and prevent any upward movement of the valve until the same is operated to withdraw the catch.
- 30 A construction of locking device according to this invention is illustrated in the accompanying drawings in which Figure 1 is a part vertical section of a locking device provided with a hydrostatically operated 35 catch. Fig. 2 is an elevation at right angles to Fig. 1 of the locking device and Fig. 3 is

a view showing in full lines the device mounted in the sinker, the sinker, drum pawl, etc., being shown in dotted lines.

As shown, the sinker comprises a shell A 60 having a base portion A'. Side plates B are mounted on the base of the sinker and in these side plates B the winding drum C is journaled. This winding drum has its cheeks C' toothed or serrated, and with these 65 teeth the pawls D are adapted to engage, the springs D' tending to normally maintain the pawls D in engagement with the toothed cheeks of the drum.

Interposed between the pawls D and the 70 plummet E is the locking device comprising our invention which is indicated as a whole by F. The locking device consists of a member 1, slidably mounted in an aperture 2 in the shell A of the sinker and provided or 75 formed at the upper end with flanges or lugs 4, to which arms or levers connected to the pawls for the winding drum ratchet are pivoted, the pivots being mounted in elongated slots 5 in the flanges or lugs to give the required lateral travel. The lower end of the member 1 is adapted to be connected to the chain of the plummet such as by a shackle 6.

The member 1 is slotted internally, to receive locking arms 7, which are mounted on 80 a common pivot 8, secured in the member, and are normally pressed outward by a spring 9, so as to tend to project beyond the sides of the member 1.

A slip band, ring or the like 10 is mounted 90 on the member 1 so as to retain the locking arms 7 within the member 1, prior to the launching of the mine gear.

A hydrostatic valve 11 of any suitable form is mounted on the sinker shell A and 95 its valve rod 12 is provided or formed with a catch 13 engaging over a correspondingly recessed part 14 of the flanges 4.

The position of the device when cocked ready for launching the mine gear is shown 100 in Fig. 1.

When the mine is launched and enters the water the plummet will sink at a faster rate than the sinker so that the member 1 is kept in a downward position by the pull of the 105 plummet chain. If the locking device was not previously cocked, the pull in the plummet chain will effect this operation. Any upward movement of the member 1 will be prevented by the catch 13 on the valve rod 110 12. On the sinker reaching a pre-determined depth the hydrostatic valve will be

forced in by the pressure of water, and the valve rod 12 will be withdrawn from engagement with the member 1, so that the only force keeping the member in a downward position is the tension in the plummet chain.

On the plummet reaching the bottom the tension in the chain is relieved and the member 1 is drawn upwardly through the opening in the sinker by the springs of the pawls, which will consequently become engaged with the ratchets on the winding drum to prevent the same from rotating and the locking arms 7 will be forced outward by the spring 8. The winding drum will now be locked and the sinker will travel to the bottom drawing the mine beneath the surface to the desired depth.

Should any pull come on the winding drum tending to rotate the same to pay out more mooring cable, or the springs of the pawls break or become otherwise inoperative so that they would not keep the pawls up to their work, the locking arms 7 by abutting 25 against the shell A of the sinker will prevent downward movement of the levers and any falling away of the pawls.

To prevent any return of the valve rod 12 to the outward position, after the first movement inward, a lock is provided consisting of a pin 15 on the rod 12, engaging in an L or like shaped slot 16 in a pivoted plate 17, which normally tends to move downward under the action of the spring 18. The bearing for the valve rod is slotted to allow the requisite travel of the pin 15. On the valve rod moving inward, and the pin 15 coming in line with the vertical part of the slot 16, the spring 18 turns the plate 19 on its pivot, 40 to bring the vertical slot in engagement with the pin and so prevent any return of the valve rod 12.

It will thus be seen that the combined hydro-mechanical device above described 45 provides for the winding drum being free to revolve at the moment of launching of the mine, thereby preventing any jerk coming on the mooring cable, for a positive locking action of the winding drum before the sinker reaches the bottom, thereby preventing the mine from remaining on the surface and disclosing the presence of the minefield, and for the mines to be laid at a pre-determined depth. Also, plummet disconnectors, which 55 are costly to manufacture and are not absolutely reliable in action are dispensed with, and the plummet and chain retained as an anchor or drag to the mine additional to the sinker. If desired an anchor plummet of 60 the construction described in the specification of application for patent may be used.

Having now particularly described and ascertained the nature of our said invention, and in what manner the same is to be per- 65 formed, we declare that what we claim is:

1. A locking device for the winding drum pawl of a submarine mine sinker of the type including a plummet, comprising a body portion extending through an aperture in the sinker and having one end connected to 70 the pawl and the other end connected to the plummet, said body portion being adapted to be drawn into the interior of the sinker, and spring actuated locking arms pivoted to said body portion for engaging the inner 75 wall of the sinker thereby locking the pawl in drum engaging position.

2. A locking device for the winding drum pawl of a submarine mine sinker of the type including a plummet, comprising a body 80 portion having one end connected to the pawl and the other end connected to the plummet, said body portion being adapted to be drawn outwardly through an aperture in the sinker under the influence of the 85 plummet, and inwardly into the interior of the sinker under the influence of the winding drum pawl, spring actuated locking arms pivoted to said body portion for engaging the inner wall of the sinker, and a slip ring normally holding said locking arms in inoperative position but adapted to be automatically withdrawn to allow said locking arms to become operative.

3. A locking device for the winding drum pawl of a submarine mine sinker of the type including a plummet, comprising locking means having one end thereof connected to the pawl and the other end connected to the plummet, a catch engaging said locking means for holding same in inoperative position, and hydrostatic means controlling said catch and adapted to withdraw said catch from engagement with said locking means.

4. A locking device for the winding drum pawl of a submarine mine sinker of the type including a plummet, comprising locking means having one end connected to the pawl and the other end connected to the plummet, a catch engaging said locking means, hydrostatic means controlling said catch and adapted to withdraw said catch from engagement with said locking means, and means for locking said catch in disengaged position.

5. A locking device for the winding drum pawl of a submarine mine sinker of the type including a plummet, comprising locking means having one end connected to the pawl and the other end connected to the plummet, a catch adapted to engage said locking means to hold same in inoperative position, hydrostatic means for withdrawing said catch from engagement with said locking means, and means for locking said catch in disengaged position, said means including a pin provided on said catch and a plate provided with an L-shaped slot in which said pin engages.

6. A locking device for the winding drum

pawl of submarine mines comprising a body portion provided with recesses, locking arms pivoted to said body portion and adapted to nest within said recesses in inoperative position and a spring for forcing said arms out of said recesses into operative position.

7. A locking device for the winding drum pawl of submarine mines comprising a body portion, locking arms pivoted to said body portion, means for urging said arms away from said body portion to locking position and means embracing said body portion and said arms and adapted to slide along said body portion to maintain said arms in inoperative position or to release them to locking position.

8. A locking device for the winding drum pawl of submarine mines comprising a body portion, locking arms pivoted to said body portion, means for urging said arms away from said body portion to locking position and a slip ring normally holding said locking arms in inoperative position but adapted to be automatically withdrawn to allow said locking arms to become operative.

9. A locking device for the winding drum pawl of submarine mines comprising a body

portion provided with recesses and locking arms pivoted to said body portion and adapted to nest within said recesses in inoperative position or to be moved from said recesses into locking position.

10. A locking device for the winding drum pawl of submarine mines comprising a body portion, locking arms pivoted to said body portion, means for maintaining said locking arms in locking position, a catch adapted to engage said body portion to maintain said device inoperative, and hydrostatic means for controlling said catch.

11. A locking device for the winding drum pawl of submarine mines comprising a body portion, locking arms pivoted to said body portion, means for maintaining said locking arms in locking position, a catch adapted to engage said body portion to maintain said device inoperative, hydrostatic means for controlling said catch, and means for locking said catch in disengaged position.

Signed at London, England, this 30th day of November, 1917.

GERARD BROOK RILEY.
HERBERT OCTAVIUS MOCK.
